Charles Marie Victor Allenou
Procurie Attorney:

UNITED STATES PATENT OFFICE

CHARLES MARIE VICTOR ALLENOU, OF NANTES, FRANCE

SAFETY DEVICE FOR AVOIDING BACK-FIRING IN CARBURETORS

Application filed December 17, 1926, Serial No. 155,518, and in France December 24, 1925.

My present invention has for its object to provide an improved safety device designed for avoiding back-firing in explosion engines towards the carburetors thereof.

5 Devices of this character heretofore known generally comprise a flap-valve which is independent from the parts of the carburetor and urged by a spring towards its closed position, said valve being normally held apart 10 from its seat by an easily fusible body.

In contradistinction to these known devices, my invention is characterized in that the member which upon the fusion of the fusible body cuts off the supply of fuel, is 15 formed of the spraying nozzle itself which will cut off the supply of fuel by its own displacement.

20 My invention is illustrated by way of example in the accompanying drawings showing the application thereof to various types of carburetors.

Figure 1 is a sectional view illustrating one form of the invention.

25 Figures 2, 3 and 4 are similar views of different forms of the invention.

Figure 5 is a sectional view, partly in elevation, of a conventional carburetor illustrating the application of the invention thereto.

In Figure 1 the spraying nozzle 1 ends 30 at its base into a cone-shaped portion 2. Said spraying nozzle 1, urged by a spring 6 bearing against a collar 7 is tightly held immovable in normal operation by a weld 3 of fusible metal or alloy, cast into a cylindrical depression 4 provided with ribs in the mass 5. Upon 35 back-firing the heating of the spraying nozzle 1 will result into the fusion of the alloy 3, the nozzle will no longer be retained in its support 5 and by the action of the spring 6 it will be moved upwardly with its bevelled or cone-shaped end portion 2. Thus the latter will be brought upon its seat 8 and cut off 40 the supply of fuel between the pipe 9 and inlet port 10.

Fig. 2 shows a modification wherein the spraying nozzle 11 having a bevelled or cone shaped lower end 12 and a spring 13, is tightly held in a corresponding recess in the mass 15 by a fusible and removable cone 14 com-

pressed by a washer 16 locked on the nozzle 11 and a nut 17.

Owing to the action of heat the liberated nozzle will cut off the supply as in the device previously described.

Fig. 3 shows a carburetor with concentric spraying nozzles, the central nozzle 18 of which may be liberated for displacement upon the fusion of an alloy. The nozzle 18 urged by a spring is slidable longitudinally in the 55 centre of the main nozzle 19 whereby the bevelled or cone shaped end portion 20 thereof will be moved upwardly. Normally the nozzle 18 is held immovable by a removable fusible cone 21, tightly housed in a suitable recess 60 in the top of the main nozzle 19 and retained therein by a collar 22. Said fusible cone is furthermore secured in place by the counter-pressure exerted by a screw-threaded member 65 23 upon a washer 24.

Upon the fusion of the cone 21 the upwardly moving nozzle 18 will bring its bevelled end portion 20 upon its seat to cut off 70 the supply as previously.

As shown the fusible cones may be arranged 75 either at the top (cone 21) or at the base (cone 25) of the main nozzle 19.

Fig. 4 shows in normal operative position a spraying nozzle 27 urged downwardly by a spring 28. Said nozzle has a hole 29 for 80 the admission of fuel and its bottom part ends into a tightly closing needle valve 30. The bottom part of said nozzle 27 is loosely surrounded by a sleeve 31 the lower part of which ends into a truncated portion 32 having an annular opening. Said sleeve 31 made 85 integral with the nozzle 27 by means of a tight weld 35 of easily fusible metal, rests tightly with its bevelled part 32 on the orifice of a fuel supply pipe 33.

Upon the firing of fuel in the opening 34 produced by back firing, the nozzle 27 heated thereby will cause the fusion of the weld 35. As now the nozzle 27 is no longer retained by the sleeve 31, the same will slide 90 within the latter and by the action of the spring 28 the needle valve 30 will close the annular opening in the truncated end 32, whereby the supply of fuel from the pipe 33 will be cut off and if necessary, by slightly 95 100

changing the diameter of said fuel pipe 33, the discharge opening thereof will be closed also.

Having now fully described my said invention, what I claim and desire to secure by Letters Patent, is:

1. In a safety device for avoiding back-firing towards the carburetor of an explosion engine, the combination of a spraying nozzle normally immovable, an easily fusible metal holding said nozzle in place, a spring urging said nozzle towards the inlet of fuel, and means on the lower end of said nozzle capable of closing the inlet of fuel upon the liberation of said nozzle by the back-fire heat, substantially as set forth.
2. In a safety device for avoiding back-firing towards the carburetor of an explosion engine, the combination of a spraying nozzle normally immovable, an easily fusible metal holding said nozzle in place, a spring urging said nozzle towards the inlet of fuel, a bevelled or cone-shaped portion at the lower end of said nozzle, and a valve seat in the fuel supply conduit cooperating with said cone-shaped portion, substantially as and for the purpose set forth.
3. In a safety device for avoiding back-firing towards the carburetor of an explosive engine, the combination of a spraying nozzle, a fixed member or part, through which said nozzle extends, a recess in said fixed member, fusible metal in said recess to hold the nozzle normally in place, a spring urging said nozzle upwardly, a bevelled or cone-shaped portion at the lower end of said nozzle, and a valve seat in the fuel supply conduit cooperating with said cone-shaped portion, substantially as and for the purpose set forth.
4. In a safety device for avoiding back-firing towards the carburetor, of an explosive engine, the combination of a spraying nozzle, a fixed member or part through which said nozzle extends, a recess in said fixed member, a truncated part of fusible metal arranged on the nozzle in said recess, a spring urging the nozzle upwardly, a bevelled or cone-shaped portion at the lower end of said nozzle, and a valve seat in the fuel supply conduit cooperating with said cone-shaped portion, substantially as and for the purpose set forth.

In testimony whereof I have hereunto set my hand.

CHARLES MARIE VICTOR ALLENOU.
